UNITED STATES PATENT OFFICE.

HERBERT S. VALENTINE, OF PHILADELPHIA, PENNSYLVANIA.

HOIST.

Application filed January 31, 1922. Serial No. 532,965.

To all whom it may concern:

Be it known that I, HERBERT S. VALENTINE, a citizen of the United States, and a resident of the city of Philadelphia, in the county of Philadelphia and State of Pennsylvania, have invented certain new and useful Improvements in Hoists, of which the following is a specification.

My invention relates to hoisting devices and particularly to those hoists which depend from and are arranged to travel upon an overhead track, and further to those hoists in which the load-block is operated by an electric motor mounted upon the carriage, and the carriage is suspended from a rail or beam, the lower flanges of which form the track for the carriage wheels.

There is a marked tendency in modern building construction to reduce to its smallest dimension the distance between the floors of a factory building, with the result that in many buildings the low head room raises a serious obstacle of the installation and to the use of overhead traveling hoists, because the carriage of ordinary hoists, and the parts mounted thereon, depend for a considerable distance below the tracks upon which the carriage is mounted.

The matter of one foot in headroom will often prevent the successful installation and use of an overhead travelling hoist particularly of the mono-rail type.

The amount of lift obtainable from an overhead mono-rail travelling hoist is necessarily limited or reduced by two factors, namely, (1) vertical height of the beam which constitutes the track or tracks on which the carriage travels, and (2) the length of the load-block, but in the hoists as heretofore constructed the vertical lift is still further reduced by the interposition of the carriage and parts mounted thereon between the rail and the block.

The object of my invention is to so construct and arrange a travelling hoist that the vertical lift is increased to the full height of the room, less the vertical height of the rail constituting the track and the length of the load-block, that is to say, to provide a construction in which the load-block may be lifted vertically until the top thereof almost touches the underside of the track rail.

A further object of my invention is to provide a hoist wherein the greatest possible lift is obtainable with a given headroom.

A further object of my invention is to so construct and arrange the carriage of a travelling hoist that none of the carriage parts or the parts of the mechanisms mounted thereon, depend below the underside of the track rail a distance greater than the length of the load-block.

A further object of my invention is to so locate and position the winding drum, the motor and the gearing for transmitting power from the motor to said drum, that the load-block, in being raised by the drum, moves vertically directly underneath the track, and between the motor and the winding drum, to and from a position where the pulley or topmost portion of the lifting block just clears, without touching, the underside of the track rail.

A further object of my invention is to provide in the carriage of a travelling hoist a clear space beneath the track into which the load-block may be raised and lowered without interference from the winding drum, the motor, or the gearing therebetween.

A further object of my invention is to so mount the winding drum and the motor for supplying the power to operate said drum, on the carriage of a mono-rail electric hoist that the two parts of the hoist on opposite sides of a plane passing vertically through the middle longitudinal line of the track or tracks are substantially balanced.

A further object of my invention is to so arrange and position on the carriage the winding drum and the anchor for the hoisting cable, that the continued rotation of the drum will lift the load-block until the top of the said block almost touches, but just clears, the underside of the track rail.

Other objects of my invention will appear in the specification and claims below.

In the drawings forming a part of this specification and in which the same reference characters are used throughout the various views to designate the same parts, Fig. 1 is a side elevational view of my improved electric hoist mounted upon an I-beam constituting the track of a mono-rail hoist.

Fig. 2 is a similar view of the opposite side of the device shown in Fig. 1, and showing the lift-block dropped somewhat below the position shown in Fig. 1.

Fig. 3 is a transverse sectional view on the line 3-3 of Fig. 5 the motor being

omitted, and its position indicated in dot and-dash lines.

Fig. 4 is an end view of the gear case or housing shown on the right hand end of Fig. 2.

Fig. 5 is a horizontal sectional view through the winding drum, and that part of the carriage which is just below the track, the motor and the gearing intermediate the motor and the winding drum being shown in plan view.

Referring now to the drawings in which is illustrated one embodiment of my invention there is provided an I-beam 1 adapted to be secured to the ceiling or other suitable support, the web 2 thereof being vertical and the lower flanges 3—3 constituting the track or tracks upon which travel the wheels or rollers 4, turning on axles 5 rigidly mounted in the upper part of the carriage 6. In suitable bearings 7—7 in the carriage is mounted the shaft 8 of the winding drum 9 the axis of said shaft 8 being arranged preferably parallel to the tracks 3—3 of the I-beam 1. On a bracket 10 and on the opposite side of a vertical plane 11 passing through the middle longitudinal line of the tracks 3—3 provided by the I-beam 1, is an electric motor 12, which may be of any well-known and approved type and construction. The shaft of this motor 12 is provided with a pinion 13 which through a suitable train 14 of spur gearing is adapted to drive the spur gear 15 rigidly secured to one end of the winding drum shaft 8. This train 14 of gearing will include a lowering brake 16 of any approved type, such, for instance, as one of the Weston type. This Weston lowering brake mechanism is a well-known construction and will need no further description in connection with this invention. The construction of such a brake is indicated in my U. S. Letters Patent No. 1,058,497 granted April 8, 1913.

The opposite end of the main shaft of the motor 12 may be and is provided with a solenoid brake 17 of any well-known and approved construction the function thereof being to apply the brakes to hold the load suspended when the power is shut off. One type of such solenoid brake is also fully illustrated in my above mentioned Letters Patent.

The train 14 of rotation gearing is mounted upon one end of the carriage 6 and is preferably enclosed in a suitable housing 18.

The winding drum 9 is preferably provided with two sets of helical grooves 19—19 each set respectively covering one half of the surface of the drum and inclined or pitched in opposite directions. The two free ends of the hoisting cable 20 are respectively secured to the ends of the winding drum 9 and lie in the outermost convolutions of the grooves

19—19. This cable 20 has therefore a loop or bight therein midway between the ends thereof, at which point it passes around an equalizing pulley 21 mounted in a yoke 22 rigidly bolted or secured to the carriage 6, this pulley and yoke forming an anchor 23 on the carriage for the middle loop of the cable. The two stretches of the cable between the surface of the winding drum 9 and the anchor 23 pass under two pulleys or sheaves 24 of the load-block 25 which, in addition to the said pulleys, comprises the stud or shaft 26, upon which the said sheaves are mounted to rotate, the guard 27 and the yoke 28 in which the shaft 26 is rigidly mounted, and from which depends the preferably swiveled load-hook 29. It is to be understood however that this load-block 25 may be of any suitable two sheave type and construction, but it is preferably one in which the overall vertical dimension is as short as it can be made, consistent with strength and flexibility of the cable to be used in the hoist.

On the opposite end of the carriage 6 there is mounted the usual controller 30 for the motor, operated by suitable controlling ropes or cable 31 depending therefrom and by which the speed and direction in which the motor 12 shall rotate is controlled and regulated.

Upon the end of the shaft 8 opposite to that on which the gear 15 is mounted and within the housing of the controller 30 there may be provided an adjustable upper and lower limit switch 32 which may be set to automatically stop the operation of the motor 12 when the block has been raised to its uppermost position and also when the cable has been unwound from the drum to any extent desired. This switch 32 may be of any well-known and approved construction, the showing in the drawings of this specification being merely diagrammatic. The mechanism is such that when the traveler 33, mounted upon a screw 34 secured to the shaft 8, reaches a predetermined position due to the rotation of the shaft 8 in one direction, it breaks the electric circuit by means of which the electric motor 12 is driven, and when the traveler 33 moves in the opposite direction to a predetermined position, due to the rotation of the shaft 8 in the opposite direction, the circuit is also broken for the same purpose.

From the above it will now be apparent that the winding drum 9 and the motor 12 are mounted on opposite sides of a plane 11—11 passing midway vertically through the I-beam 1 and midway between the tracks 3, and that these heavy parts are so disposed that they tend to balance the carriage and parts carried thereby on each side of said plane. This construction also provides a considerable space between the winding

drum 9 and the motor 12, said space being greater than the diameter of the pulleys 24 of the load-block 25, in fact it is wider than the extreme width of the block so that there is provided in the carriage, between the parts thereof, sufficient space for the vertical travel of the block 25 therebetween up to a point directly under, and close to, but just out of contact with the under side of the flanges 3 of the I-beam 1.

In order that said block 25 may be lifted to such position, the axis of the winding shaft 8 is located in the carriage 6 above a horizontal plane 35 which is below the plane 15 of the under surface of the I-beam a distance not greater than the radii of the pulleys or sheaves 24 of the load-block 25. As above stated the axis of the winding shaft 8 is preferably parallel to the track 3-3 and therefore it is located on one side of the vertical plane 11 and at a distance therefrom not less and preferably a little more than the sum of the radii of the drum 9 and a sheave pulley 24. The electric motor 12 is also so located that the inner side of the outside casting or lining thereof is spaced from said vertical plane by a distance sufficient to prevent any contact therewith of the cable 20 between the anchor 23 and the sheave pulleys 25 24.

The electric motor 12 is also spaced from the middle vertical plane 11 of the tracks at a distance not less than the radius of a sheave pulley 24, or one-half the width of the load-block 25, so that at all times it will be out of contact with the load-block and that stretch of the cable between the load-block and the anchor 23. In this way a free space is provided in the carriage between the motor and the winding drum and underneath the I-beam 1 and tracks 3 sufficiently wide to permit of the travel of the load-block therebetween up to a position immediately beneath, and out of contact with the under side of the I-beam or track rail.

It is clearly shown in Figs. 1 and 2 that neither the controller 30 of the motor nor the housing 18 for the gearing 14 between the motor 12 and the winding drum 9 extend below the underside of the I-beam 1 a distance substantially greater than the total length of the load-block 25. No part of the carriage or the rigid parts mounted thereon, will interfere with the clear rise of the load-block 20, to a point where it almost touches the track beam. No part of the carriage depends below the load-hook 29, when the load-block 25 is lifted to its highest position.

By reason of the construction and arrangement above described, I am able to effect, in a hoist of the mono-rail type, the greatest vertical lift possible, with a given head room and the increase in the lift over that obtainable in other hoists of this type is very substantial. Thus, for a two-ton hoist of the

ordinary mono-rail type, the hook of the load-block cannot be raised higher than within about 42 inches from the underside of the rail, and generally, this distance is considerably greater, up to 40 or 53 inches. 70 In my construction, however, the load-hook of a hoist of the same capacity can be readily lifted to within 11 inches of the underside of the rail. This increased lift of from 31 to 42 inches over that obtainable in the ordinary hoist becomes very important whenever the head-room is low. 75

It is to be understood that the carriage and the parts mounted thereon, including the electric motor, the winding drum, the controller, and the gearing, constitute the rigid parts of the hoist, and that these rigid parts usually decrease the lift obtainable from a hoist by reason of their disposition on the carriage. In my improved hoist, none of these parts depend below the underside of the rail a distance substantially greater than the length of the load-block. It is not to be understood, however, that my improved hoist may not be provided with the usual ropes, cables or chains depending from the controller to a point within easy reach from the floor, but such controller cables or chains are flexible and can be readily swung or deflected to any suitable position out of the way of any object which may be swung from the hook or anything below the carriage. 85

Having thus described my invention what I claim and desire to protect by Letters Patent of the United States is: 100

1. In a mono-rail hoist the combination of an overhead mono-rail track, a carriage depending therefrom and adapted to travel on the lower flange thereof, a load-block and means mounted on said carriage to raise and lower said block in a vertical path directly under said track to and from a position wherein the top of said block is immediately below but out of contact with the under side of said track, no rigid part of said carriage or the parts carried thereby depending below said track a distance substantially greater than the height of said block. 110

2. In a mono-rail hoist comprising a mono-rail track, a carriage suspended from said track and adapted to travel thereon, the combination of a winding drum, a hoisting cable secured thereto, an anchor for said cable, a load-block comprising a pulley resting in the bight of said cable between said drum and said anchor and hanging directly beneath said track, said drum and said anchor being mounted on said carriage on opposite sides of a vertical plane in which lies the middle longitudinal line of said track, and providing between them a clear space for the vertical travel of said block up to substantially the under side of said track the axis of said drum being horizontal and located above a horizontal plane located be- 125 130

low the under side of said track a distance not substantially greater than the radius of said pulley and means mounted on said carriage to rotate said winding drum.

5. In a hoist comprising a mono-rail track, a carriage depending from said track, the combination of a winding drum, a cable attached to said drum, an anchorage on said carriage for said cable and a block comprising a pulley and hook mounted in the bight of said cable, said drum and said anchorage being on opposite sides of a vertical plane in which lies the middle longitudinal line of said track and spaced apart a distance substantially equal to the diameter of said pulley, the axis of said drum and said anchorage being above a plane passing horizontally under said track at a distance not substantially greater than the radius of said pulley, and said carriage providing an open space extending vertically therethrough below said track of a size to permit the entrance of said pulley therein, no part of said carriage extending below said rail a distance substantially greater than the length of said block.

4. In a hoist comprising an overhead mono-rail track a carriage suspended from said track and adapted to travel thereon, the combination of a winding drum the axis of which is parallel to the track, mounted in said carriage on one side of a vertical plane in which lies the middle longitudinal line of said track, a cable secured to said drum, an anchorage on said carriage for said cable and located on the opposite side of said vertical plane, a block having a pulley and hook suspended on said cable between said anchorage and said drum, a motor mounted on said carriage on said opposite side of said vertical plane and operative to balance the weight of said drum gearing for transmitting power from motor to said drum, said gearing being mounted on one end of said carriage and a housing enclosing said gearing, said winding drum and anchorage being spaced apart horizontally a distance substantially equal to the diameter of said pulley and said carriage being provided with a clear space vertically substantially therethrough beneath said track, no rigid part of said carriage depending below the plane of the underside

of said track a distance greater than the length of said block.

5. In a hoist comprising a mono-rail track, a carriage depending therefrom and mounted to travel thereon, the combination of a winding drum mounted on said carriage with its axis parallel to said track, an anchor secured to said carriage, a cable secured to said drum and anchor and depending in a bight therebetween, a load-block provided with a pulley riding in said bight, a motor, and means to transmit the power of said motor to said drum, said drum being on one side and said motor and anchor on the opposite side of a vertical plane in which is the middle longitudinal line of said track, and providing between them a clear space beneath said track of a width greater than the width of said block and the axis of said drum being above a horizontal plane spaced from the under side of said track by a distance not substantially greater than the radius of said pulley.

6. In a hoist comprising a mono-rail track, a carriage depending therefrom, and mounted to travel thereon, the combination with a winding drum mounted on said carriage with its axis parallel to said track, an anchor secured to said carriage, a cable secured to said drum and anchor and depending in the bight therebetween, a load-block provided with a pulley riding in said bight, a motor, and means to transmit the power of said motor to said drum, said drum being on one side and said motor and anchor being on the opposite side of a vertical plane in which is the middle longitudinal line of said track, said anchor being spaced horizontally from said plane at a distance greater than the radius of said pulley, the axis of the drum being spaced horizontally from said vertical plane a distance greater than the sum of the radii of said drum and pulley and above a horizontal plane spaced from the under side of said track by a distance not substantially greater than the radius of said pulley.

In witness whereof, I have hereunto set my hand this 27th day of January, 1922.

HERBERT S. VALENTINE.
